UNITED STATES PATENT OFFICE.

BENJAMIN BOLEY, OF BROOKLYN, NEW YORK.

DESIGN FOR A BOTTLE-STOPPER PLUG.

SPECIFICATION forming part of Design No. 25,917, dated August 11, 1896.

Application filed July 30, 1895. Serial No. 557,638. Term of patent 7 years.

To all whom it may concern:

Be it known that I, BENJAMIN BOLEY, a citizen of the United States, and a resident of Brooklyn, in the county of Kings and State of New York, have invented and produced a new and original Design for Bottle-Stopper Plugs, of which the following is a specification.

This invention relates to a design for the plug of a bottle-stopper, as shown in the accompanying illustrations, wherein—

Figures 1 and 2 are side elevations, and Figs. 3 and 4 top and bottom plans, respectively.

The leading feature of this design resides in the configuration of the plug as an entirety.

In the accompanying drawings, which form a part of this specification, 1 represents the body of the plug, having a circumferential groove 2 near the bottom, the body being approximately of trunco-pyramidal shape, sur-

mounting which and larger in diameter is a circular plane-sided head 3. Traversing the head and extending above it is an arch-shaped rib 4, and in the rib is an elongated and upwardly-disposed aperture 5, its lower portion merging into depressions 6 in the top surface of the head 3.

The end 7 of the body 1 is dish-shaped.

Having thus described my invention, I claim—

The design for a bottle-stopper plug, substantially as herein shown and described.

Signed at New York, in the county of New York and State of New York, this 24th day of July, A. D. 1895.

BENJAMIN BOLEY.
